UNITED STATES PATENT OFFICE.

AUGUST H. BECKMAN, OF MADISON, WISCONSIN.

BUILDING ELEMENT.

1,052,207.

Specification of Letters Patent. Patented Feb. 4, 1913.

Application filed March 18, 1912. Serial No. 684,381.

To all whom it may concern:

Be it known that I, AUGUST H. BECKMAN, a citizen of the United States, residing at Madison, in the county of Dane and State of Wisconsin, have invented certain new and useful Improvements in Building Elements, of which the following is a specification.

The present invention has for its object to provide a metallic building element to take the place of wooden structural members in building construction, the design of the element being such that it can be used for studding, joists, rafters, partition studs, and various other parts of a building.

The invention also has for its object to provide novel and improved attaching devices to be used in connection with the element.

Other objects and advantages of the invention will be manifest from the detailed description appearing hereinafter, and in order that the invention may be better understood reference is had to the accompanying drawings forming a part of this specification, in which drawings—

Figure 1 is an elevation of the element. Fig. 2 is a cross section thereof on the line 2—2 of Fig. 1. Fig. 3 is a perspective view of the fastener employed in connection with the element. Fig. 4 is a sectional view showing the element employed in connection with a floor. Fig. 5 is a vertical section of a building construction showing a further application of the element. Fig. 6 is a vertical section showing a window construction.

As shown in the drawings, the element comprises a built-up beam having a hollow web and outstanding flanges. The beam is composed of two longitudinal members 10 and 11, respectively, each of which members has outstanding flanges 12 at its longitudinal edges, which flanges, when the two members are assembled face to face to form the beam, extend outwardly from opposite sides of the latter at its longitudinal edges. The two members have the same cross-sectional shape, said shape being such that the beam is given a hollow web. As shown in Fig. 2, the members are parallel for a short distance from their longitudinal edges, and then extend divergently in the direction of the middle portion of the beam to form the hollow web thereof, the members being channel shaped in cross section at the last mentioned portion of the beam, as indicated at 13. The channel portions of the members

face each other and are on the inside of the beam. Between the members, at suitable intervals, and extending between the top and bottom thereof, are located reinforcing bars 14 which are secured in place by bolts 15 passing through the parallel portions of the members. The beam is also reinforced at its ends by strips 16 secured to both sides of the web on the outside thereof, said strips being fastened by bolts 17 passing through the parallel portions of the members. The bolts 15 and 17 also serve to fasten the members together in assembled relation. The beam is also trussed by a cable or rod 18 located between the members and extending from one end to the other. The truss is made fast at its ends by any suitable means between the upper parallel portions of the members, and thence extends downwardly, its intermediate portion being located between the lower parallel portions of the members.

The middle portion of the beam has holes for spacing bars 19, said bars passing through the holes and being made fast by cotter pins 20 passing through the bars on opposite sides of the beam contiguous to the channeled portions of the members constituting said beam. These holes may also be employed for electric wiring, in which event they will be lined with a suitable insulating bushing 21.

When the beam herein described is employed as a joist in floor construction, as shown in Fig. 4, a number of such beams are positioned in spaced relation by means of the bars 19. The nailing strips 22 to which the flooring 23 is secured, are supported on the top flanges 12 by the fastener shown in Fig. 3. This fastener comprises a sheet metal plate 24 having tongues 25 at its ends, on both sides, diametrically opposite ones of which tongues are adapted to be bent under the top flanges 12 to hold the fastener in place. The plate also has spurs 26 on opposite sides which are bent inwardly and driven into the sides of the strip 22.

The channeled portions 13 of the beam members may be employed to support the arched form 27 which supports the concrete 105 filler 28 located between the beams.

Fig. 5 represents a vertical cross section of a building construction showing the method of placing the floor joists shown in Fig. 4 on the stone or brick wall 29, and also the method of supporting the floor joists of the next floor. To the top flanges

of the first-mentioned joists are fastened, by means of rivets or other suitable means, one of the members of which the herein-described beams are composed, and a similar 5 member is secured to the bottom flanges of the joists of the next floor. Between these members extend studding members which are formed of the herein-described beams set in vertical position. The plaster board 30 is 10 fastened by means of prongs 31 stamped in the studding member in such a way that when placing the plaster board the same is set in between the studding members, and the prongs are bent out against the plaster 15 board to hold the same in place.

A plaster board or metal lath 32 for the wall and ceiling is fastened to the face of the studding, and to the bottom flanges of the floor joists, using the fastening device 20 shown in Fig. 3.

Fig. 6 shows a window construction. The studding members are cut away to form the opening for the window frame 33, the space between the two trimmers 34 representing 25 this opening. Each trimmer is composed of one of the members of which the herein-described beam is formed.

I claim:

1. A building element comprising a beam 30 composed of a pair of longitudinal members each having outstanding flanges at its

longitudinal edges, said members being parallel for a portion from their longitudinal edges, and then extending divergently in the direction of the middle portion of the beam to form a hollow web, said diverging portions terminating at the middle of the beam in a portion which is channel-shaped in cross-section, the channels facing each other and being located on the inside of 40 the beam.

2. A building element comprising a beam composed of a pair of longitudinal members each having outstanding flanges at its longitudinal edges, said members being parallel for a portion from their longitudinal edges, and then extending divergently in the direction of the middle portion of the beam to form a hollow web, said diverging portions terminating at the middle of the beam in a portion which is channel-shaped in cross-section, the channels facing each other and being located on the inside of 45 the beam, and a reinforcing member held between the aforesaid parallel portions of 50 the members.

In testimony whereof I affix my signature in presence of two witnesses.

AUGUST H. BECKMAN.

Witnesses:

MIKE GEIER,
H. S. WILLIAMS.
